US00D961187S

(12) United States Design Patent (10) Patent No.: US D961,187 S
(45) Date of Patent: * Aug. 23, 2022

(54) FOOD PRODUCT

(71) Applicant: Luigi Fiorentino, Brooklyn, NY (US)

(72) Inventor: Luigi Fiorentino, Brooklyn, NY (US)

() Term: 15 Years

(21) Appl. No.: 29/627,964

(22) Filed: Nov. 30, 2017

(51) LOC (13) Cl. 01-01

(52) U.S. Cl.

USPC D1/126; D1/120; D1/130

(58) Field of Classification Search

USPC D1/100-130, 199; 426/94, 138, 143,

426/275, 277, 279, 281-284, 292, 295,
